Primary Examiner — John Windmuller*(74) Attorney, Agent, or Firm* — Frost Brown Todd LLC(57) **CLAIM**

The ornamental design for a bridging clip, as shown and described.

DESCRIPTION

FIG. 1 is a top perspective view of a bridging clip, showing our new design;

FIG. 2 is a bottom perspective view thereof;

FIG. 3 is a top plan view thereof;

FIG. 4 is a bottom plan view thereof;

FIG. 5 is a left elevation view thereof;

FIG. 6 is a right elevation view thereof;

FIG. 7 is a front elevation view thereof, wherein the bridging clip is in an inverted orientation; and,

FIG. 8 is a rear elevation view thereof, wherein the bridging clip is in an upright orientation.

The elongated channel shown in broken lines in FIG. 1 is unclaimed subject matter, and does not form a part of the claimed design.
